US0D1109453S

(12) **United States Design Patent** (10) **Patent No.:** **US D1,109,453 S**
(45) **Date of Patent:** **** Jan. 13, 2026**

(54) **CAT SCRATCHER**

(71) Applicant: **PETAVERSE AUSTRALIA PTY. LTD**, Sydney (AU)

(72) Inventor: **Bei Hong**, Shanghai (CN)

(**) Term: **15 Years**

(21) Appl. No.: **35/523,965**

(22) Filed: **Jan. 16, 2025**

(80) **Hague Agreement Data**

Int. Filing Date: **Jan. 16, 2025**

Int. Reg. No.: **DM/243812**

Int. Reg. Date: **Jan. 16, 2025**

Int. Reg. Pub. Date: **Feb. 7, 2025**
